ERWIN LEHRER, OF LUDWIGSHAFEN-ON-THE-RHINE, GERMANY, ASSIGNOR TO I. G. FARBENINDUSTRIE AKTIENGESELLSCHAFT, OF FRANKFORT-ON-THE-MAIN, GERMANY

MAGNETIC PISTON PUMP

Application filed April 25, 1931, Serial No. 532,748, and in Germany April 28, 1930.

The present invention relates to improvements in magnetically operated piston pumps.

Pumps for the movement of gases and liquids are already known in which the pistons consisting of a piece of iron are moved backwards and forwards horizontally by the attractive power of coils traversed by currents.

I have now found that the regulation of the magnet coils may be effected simply and surely by an electromagnetically operated pendulum with two contacts by which the coils are alternately connected to the source of current. It is especially advantageous to arrange the two contacts in an annular tube in which there is mercury which effects the closure of the circuit by the movement of the pendulum. Other forms of contact may of course be employed instead of an annular tube, as for example two separate contacts which the pendulum strikes.

In order to reduce the great friction produced by the horizontally moved piston and which must be overcome by the magnetic attraction, it is preferable to arrange the piston in a vertical cylinder and to take the load thereof, for example with a spring. In this manner the friction of the piston is reduced to a minimum and the efficiency of the pump is considerably improved.

Instead of metallic pistons, a column of liquid in a U-tube may be employed as the piston, the liquid being set in oscillation, by means of one or two ferromagnetic cores floating on one or both legs of the liquid, the cores being operated by one or two electromagnetic coils.

A special advantage in the employment of liquid columns instead of metallic pistons consists particularly in the completely pressure-tight closure obtained without appreciable increase in the loss caused by friction. It is therefore possible with such pumps to move equal volumes of different gases at the same time. When only one gas is to be moved, the suction and outlet openings of the valve member are preferably joined together.

It is preferable to excite the coils in correspondence with the frequency of the os-

cillations of the column of liquid because the efficiency of the pump is thus increased.

The nature of the invention will be further described with reference to the accompanying drawings which illustrate, diagrammatically and partly in section, arrangements of apparatus according to this invention, but the invention is not restricted to these arrangements.

Figure 1 is a vertical section through a pump having a reversing device which is actuated by a pendulum operated electromagnetically. Figures 2 and 3 illustrate modifications of the pump in vertical section, each piston of these pumps being replaced by a liquid on which float one or two ferromagnetic cores.

Referring to Figure 1, a ferromagnetic piston *c* which is readily movable but without play is suspended on a spring *d* in a vertical cylinder *a* having a lateral joint *b*. Two windings *e* and *f*, as for example two copper wire coils, are wound round the cylinder *a*. They are alternately joined to a source of current by a commutator *U*. The piston *c* is thus moved up and down, the liquid or gas to be moved being sucked in through the lower valves of the valve member *g* and forced out through the upper valves. The commutator *U* which serves for regulating the magnet coils *e* and *f* is constructed as an annular tube *m* having a mercury filling by which the contacts *p* or *o* are joined to *n* according to the position of the pendulum *h*. The pendulum *h*, having a movable pendulum body *i* is operated electromagnetically by means of the coil *l* by which an iron body *k* consisting of strips of sheet iron is attracted. The connections of the coil *l* to the commutator *U* will be seen from the drawings.

In order to obtain a uniform and quiet operation of the pump and still further to improve its efficiency it is advantageous to adjust the oscillations of the pendulum to the peculiar oscillation of the piston-spring system by moving the pendulum body *i*.

Moreover, it is preferable to prepare the piston *c* not from a massive piece of iron but from a tube filled with strips of sheet iron

because the pump may then be actuated by alternating current, contrasted with the direct current hitherto almost exclusively employed, which necessitated either a transformer aggregate or the presence of a battery of accumulators.

Referring to Figure 2, which illustrates a pump in which the piston is replaced by a column of liquid, a liquid *o*, as for example 10 mercury or another liquid having a very high specific gravity and a low vapor tension is placed in a U-tube *p*. On one arm of the column of liquid floats an iron core *q*. Two coils *f* and *e* are wound round this and are 15 provided with three contacts 1, 2 and 3. The contacts 1 and 2 are connected with a commutator as shown in Figure 1 which alternately connects the coils with a source of current. The contact 3 is connected directly to one pole of the source of current. The upper ends of the U-tube *p* are closed by the valve members *r* and *s* through which the material to be moved is sucked in at the bottom and forced out at the top by the movement of the column of liquid.

Referring to Figure 3, which illustrates a modification of the pump shown in Figure 2, iron cores *t* and *u* float on both arms of the column of liquid *o*. The arms of the U-tube 20 each have a coil *e* and *f* having contacts 4, 5 and 6 which are connected as described in regard to Figure 2. The method of operation is similar to that described with reference to Figure 2.

35 In the appended claims the term "ferromagnetic piston" is used to include both the metallic form of piston hereinbefore referred to as well as a liquid serving as the piston and bearing one or more magnetic floats.

40 What I claim is:

1. In a fluid pump, in combination a vertical cylinder, a ferromagnetic piston in said cylinder, at least one coil on said cylinder adapted to periodically act on said piston, 45 and a pendulum provided with current leads and contacts, thereby periodically connecting said coil to a source of current.

2. An arrangement as claimed in claim 1 in which two coils are provided and these are 50 alternately connected to said source of current.

3. An arrangement as claimed in claim 1 in which two coils are provided and these are 55 alternately connected to said source of current and in which the pendulum is provided with an annular tube containing three contacts and being partly filled with mercury so that the mercury makes an electric conduit between two of the said three contacts alternately on oscillation of the pendulum.

4. In a pump, in combination a vertical cylinder, a ferromagnetic piston in said cylinder, a spring in said cylinder taking the load of said piston, at least one coil on said cylinder adapted to periodically act on said pi-

ton, a pendulum provided with current leads and contacts, thereby periodically connecting said coil to a source of current, and a pendulum body moyably arranged to adjust the oscillations of said pendulum to the specific 70 oscillations of said piston.

5. An arrangement as claimed in claim 4 in which said pendulum is operated electro-magnetically.

In testimony whereof I have hereunto set 75 my hand.

ERWIN LEHRER.
